FUSE FOR PROJECTILES

John B. Semple, Sewickley, Pa.

Application January 27, 1941, Serial No. 376,079

4 Claims. (Cl. 102—80)

This invention relates to fuses for projectiles; and, while of general applicability, it has been developed in application to fuses for shells for guns of small calibre, and particularly anti-aircraft guns. The objects in view are simplicity of structure combined with safety in handling and firing and certainty in functioning.

In the accompanying drawings Fig. I is a view in axial section, and to enlarged scale, of a fuse in which the invention is embodied. The invention centers in a certain detonator block movable in its mounting within the fuse body from unarmed and safe position to active, armed position; and, in Fig. I, this detonator block appears in elevation and in its inactive and safe position. Fig. II is a view corresponding in other respects to Fig. I, in which, however, the detonator block appears partly in section and in its active, armed position. Fig. III is a view in side elevation of the detonator block alone, and in this view (as also in Fig. I) a certain set-back bolt that the detonator block carries is shown in the extended position that it maintains while securing the detonator block in unarmed and safe position. Figs. IV and V are views of the detonator block in transverse section, on the planes indicated severally at IV—IV and V—V, Fig. III. Fig. VI is a view corresponding in other respects to Fig. III, but showing the set-back bolt in the retracted position to which it comes, leaving the detonator block free within the fuse body to move to armed position. Fig. VII is a view to larger scale and in section showing the detonator block and immediately adjacent portions of the body. The plane of section is indicated at VII—VII, Fig. III. Fig. VIII is a view in plan of an element that in Fig. VII is shown in section. Fig. IX is a fragmentary view to larger scale of a portion of the structure as seen in Fig. I and illustrating a refinement in detail. In this figure, however, the detonator block is shown in vertical and axial section. Fig. X is a view in elevation of an element that in Fig. IX is shown in section. Figs. XI and XII are views in axial section, and on planes at right angles to one another, of a modified fuse in which the detonator block of the invention is adapted to and combined with a simplification of firing mechanism.

Referring first to Figs. I—VIII, a fuse is shown arranged within a body 1. The body 1 will be recognized to be the anterior pointed end of a shell, adapted to be screwed to place in assembly with the essentially cylindrical body of the shell. This anterior end of the shell becomes indeed the fuse body. It is an integral, one-piece body, as-

sembled with the shell by means of a single screw-thread union. This fuse body 1 is formed with an axial bore 2, and through the bore, in the functioning of the fuse, the firing of a primer 3 is transmitted rearwardly to a booster charge 4 that fills an enlargement of the bore and that (as will be understood) is, in the assembly, in position to transmit detonation to the burster charge that fills the body of the shell.

10 A transverse cylindrical bore 5, whose axis lies in a common plane with that of the axial bore through the fuse body, is sunk in the side of the integral body 1 toward the opposite side. It extends beyond the axial bore through the body 1 but does not penetrate to the opposite side of the body 1. It intersects at right angles the axial bore 2. In this transverse bore an essentially cylindrical detonator block 6 is carried. Transversely through the detonator block extends a diametrical bore 7, and the parts are so arranged and proportioned that, in the range of turning of the block within its bore, its diametrically extending bore comes from a remote position to a position of coincidence with and indeed forms part of the axial bore through the fuse body. That is to say, the detonator block 6 is a make-and-break device that, in alternate positions, either obstructs or establishes the continuity of the axial bore through the fuse body. The diametrically extending bore 7 through the detonator block is filled with a column of detonation-transmitting material, conveniently assembled within a capsule and then brought to place within the bore. The column within the bore, in this instance, includes the charge 3 of primer composition itself, backed by a ported anvil block 8 (cf. Figs. VII and VIII) and covered by a suitable penetrable protective septum 9, as of metal, and, in succession, to rearward of the primer composition the charge includes a body 10 of lead azid or other initiating explosive, and a body 11 of tetryl, the substance of which the booster charge 4 also is composed.

45 In the embodiment of the invention shown in Figs. I—VIII a firing pin 12 is arranged in the anterior end of the axial bore through the body 1. When the detonator block 6 is in armed position the body 3 of primer composition is in position for the impingement upon it of the firing pin. 50 The firing pin 12 consists of a shank pointed at the posterior end and provided at the anterior end with an enlarged head that is arranged within the widened forward end of the bore 2, with clearance for free movement. A protecting septum 13, a thin plate of aluminum for example,

closes the bore at the forward end. Sufficing for ordinary protection and for the exclusion of dirt and moisture, this cover-plate 13 is destructible upon impact of the shell upon a target, so that the force of the impact, communicated to the firing pin, drives the pin rearward within its bore, causing it to penetrate the septum 9 and fire the body 3 of primer composition. The ensuing flash of the charge, passing through the ports in the anvil plate 8, reaches and detonates the body 10 of lead azid or other initiating explosive. Detonation of body 10 imparts detonation to body 11 and through body 11 to the booster charge 4, with which the body 11 is, in this position of the detonator block, functionally continuous.

The unarmed and safe position of the detonator block is that shown in Figs. I and VII; and, specifically, when in this position the detonator block 6 is turned through an angle of 60° counter-clockwise from its armed, firing position. So long as the detonator block continues in this unarmed position, the fuse is safe. Premature and accidental firing of the sensitive body 10 of lead azid cannot reach booster charge 4 to fire it.

The diametrical bore 7 through the detonator block 6 is, as shown in Figs. I and II, arranged in a medial portion in the length of the block, leaving the ends of the block 6 to be adapted in particular ways and to serve particular purposes. In one end of the block (the left-hand end, as seen in Fig. I) a diametrical bore is formed, and is so placed that, when the block 6 is in its unarmed position, this bore extends in fore-and-aft position, parallel with the axis of the shell. In this bore a set-back bolt 14 is arranged, and the set-back bolt is by a shear-pin 15 normally secured in the protruding position shown in Figs. I, III, and V. When in its extended position the set-back bolt at its anterior end extends into a slot 16 cut in the rim of bore 5 for its reception, and so secures the detonator block against turning. The bore 5, open to the left for the introduction of the detonator block, is closed by a screwed-in block 17, the bore being widened, so that the applied block closes the slot also. The inner smooth right-hand face of the block 17 forms in the assembly an end wall of the cylindrical chamber within which the detonator block 6 is arranged.

The detonator block 6 at its opposite, right-hand end is cut away. Diametrically opposed recesses 18 are formed that leave between them a diametrically extending vane 19. It will be found advantageous to form the recesses 18 as shown in Fig. IV, in the shape of symmetrically placed segments of cylindrical bores sunk in the head of the cylindrical block 6. Thus in simple manner the mass of the remaining vane 19 is widely distributed from the axis of the block 6. The vane 19 is so disposed that, when the block is in its unarmed position (Figs. I and VII), the vane is in the oblique position shown in Figs. I and IV. When the shell is in flight, rotating as it flies, and when the detonator block is free within its bore, centrifugal force, acting upon the block with this obliquely disposed vane will effect a turning of the block within its bore until the mass, previously unbalanced, comes to balance with respect to the impelling force, that is to say (other things being equal), until the mid-diametrical plane of the vane 19 is perpendicular to the axis of shell rotation. In case the block 6 with its bore 7 in

alignment with the bore 2 is not in the distribution of its mass truly symmetrical with respect to the fuse axis, the position of the vane 19 will be minutely adjusted empirically, to afford compensation for such asymmetry. But for that, the vane will be so placed that its mid-diametrical plane is perpendicular to the axis of bore 7. Centrifugal force then will be effective upon the block 6 to turn it clockwise (Figs. IV and VII) until the vane 19 extends exactly in perpendicular position (Fig. II) and bore 7 is exactly aligned with bore 2.

Restating this matter, the mass of the detonator block is, by virtue of the vane 19, asymmetrical with respect to its cylindrical axis; and, when in unarmed position and in rotation on the shell axis (an axis perpendicular to its own axis), it is in a state of unbalance with respect to the centrifugal force due to such rotation. In consequence, it turns upon its own axis until it comes to a position of balance with respect to such centrifugal force. That position of balance is the armed position.

It is to be observed that, by the provision of the vane 19 extending from the block 6, such small asymmetry as may be due to difference in mass between the body of the block and of the charge that fills the bore within it is cloaked and rendered ineffective: the asymmetry afforded by the vane will be quantitatively greater and prevailing in effect.

It is advantageous that a slight indentation or recess 20 be formed in the cylindrical surface of the detonator block 6, so placed that, when block 6 is assembled in the unarmed position in which it is secured by the set-back bolt 14, the recess will come to position in the axis of the shell and to rearward of the firing pin—the position shown in Fig. I.

On firing, the bolt 14, setting back under inertia, shears the pin 15, and comes to the position shown in Fig. VI. The same impulse of firing causes the firing pin to set back into recess 20, and this engagement of the firing pin in recess 20 will continue so long as the shell is under acceleration: that is to say, until after the shell leaves the gun. And, although the shell is set in rotation, this engagement of the firing pin in recess 20 is effective, to secure detonator block 6 in its unarmed position. That is to say, the fuse is bore-safe. When, however, the shell has left the gun and the acceleration of the firing charge is spent, centrifugal force exerted upon the unbalanced detonator block 6 is effective to turn the block within its bore, forcing forward the firing pin 12 that now offers no effective resistance. This turning under centrifugal force carries the block 6 from unarmed (Fig. I) to armed position (Fig. II) and maintains it during flight in armed position. On impact, the firing pin is driven rearward, penetrating the body of primer composition. The fuse functions, and the shell is detonated.

So long, however, as the bolt 14 continues, locked by the shear-pin in its extended position, the shell cannot be detonated, even though the initiating elements of the fuse might prematurely be fired.

It will be remarked of the fuse thus shown and described that it is a structure of notable simplicity and strength; the parts are of such shape as to permit of die-casting; very little machining has to be done upon them; and only two screw-threads have to be cut. The detonator block is

integral; it is of simplest contour, essentially cylindrical. In its medial portion it is penetrated by a charge-carrying bore; at one end it is recessed to receive the set-back bolt; and at the other end the cylindrical contour is cut away, to afford functional unbalance. Assembly is very simply effected. The detonator block 6, equipped with its pin-held set-back bolt 14, is loaded with its charge (which, previously prepared, and contained in a capsule, may be slipped to place), and is applied as a unit to the unitary fuse body 1 (in which the booster charge 4 has already been placed). In making application, the protruding end of the set back bolt 14, engaging the slot 16, brings the detonator block precisely to position (to the unarmed, safe position). The closure 17 is then applied. The firing pin is introduced through the nose of body 1, and the closure 13 is applied. The component parts are easily produced, and easily assembled, and all is inexpensive. All this with precision and certainty in functioning, so that the fuse is at once simple in unexcelled degree, safe in unexcelled degree, and sure in unexcelled degree.

Fig. IX illustrates a modification in which, beneath the block 17a that closes the bore 5, a plate 21 is introduced. It may be a thin plate of aluminum. This plate may be placed in a rebated seat in the body 1. It has a lip 22 outstanding from its otherwise circular margin, of such size and shape as to fill the groove 16, to the exclusion of dirt. Such a plate being provided, secured in place beneath block 17a, it is not necessary that the block 17a be enlarged, itself to cover and enclose the groove 16.

In the modification shown in Figs. XI and XII there is no firing pin. The primer composition 3c suitably protected in a light metal carrier is arranged in the forward end of the axial bore 2c, and rests to rearward upon an anvil 8c rigidly mounted in the body 1c. The primer charge under stress of impact will be fired upon the anvil. The anvil is ported, and the flash of firing is delivered rearward through bore 2c. The charge in the detonator block 6c in this case consists of the body 10c of lead azid upon which (suitably protected, as by shellac) the flash from the primary charge makes immediate impingement. To the rear of the body of lead azid is the body 11c of tetryl. With the modifications indicated, the structure functions in the manner described.

In all of the figures the block is shown to be of such length as substantially to fill the bore from end to end. In Fig. XI the block is shown to be round-ended; and, in consequence, it turns the more freely in the bore. The transverse bore 5c for the detonator block 6c extends completely through the block 1c and is closed at the ends by an encircling band 17c.

The structure of the invention in all of its

forms includes—indeed, is characterized by—a detonator block that is arranged in a transverse bore in the fuse body and that turns under centrifugal force from unarmed to armed position; a detonator block that in its turn is provided with a transverse bore. The transverse bore in the detonator block carries a charge, and this charge in the turning of the detonator block, is brought from a position of safety to an armed position, in which it is aligned with and forms part of a line of ignition and detonation from firing means at the nose to a booster charge at the base of the fuse body. The turning of the fuse body upon its transversely disposed axis is effected by centrifugal force incident to shell rotation effective upon a detonator block whose mass is with respect to that force unbalanced.

I claim as my invention:

1. A fuse for a projectile including a body having a transverse open end bore and an intersecting longitudinal bore, the transverse bore having an outwardly opening groove in its rim, a cylindrical detonator block insertable laterally in said bore for rotatable mounting therein and responsive to centrifugal force to arm the fuse, said block being provided with a bore extending diametrically therethrough for reception of a primer and adapted to register with the longitudinal bore when the fuse is in armed condition, said block being further provided with a recess, a setback bolt in said recess and provided with a protuberance extending into said groove to hold the block in unarmed position and to guide the block in inserting it in the transverse bore, a pin normally holding the bolt above the bottom of the recess, said pin being arranged to be sheared upon setback to allow the withdrawal of the protuberance from said groove to partly arm the fuse, the structural relationship between the block and fuse body being such that the block and parts carried thereby are insertable laterally in said body as a unit, and means for closing the open ends of the transverse bore and groove.

2. The invention of claim 1 characterized in that the transverse bore in the fuse body is of greater diameter at its open end than the diameter of the block and sufficiently so to include the depth of said transverse groove, and unitary means for closing the outer end of said transverse bore including said groove.

3. The invention of claim 1 characterized in that the means for closing the transverse bore comprises a block threaded into the open end of the bore.

4. The invention of claim 1 characterized in that there is a diametrically disposed vane at the inner end of the rotatable block, said vane increasing in cross-sectional area from the axis of said block to its periphery to increase the mass of the block adjacent its periphery.

JOHN B. SEMPLE,
